UNITED STATES PATENT OFFICE.

SPENCER HEATH, OF WASHINGTON, DISTRICT OF COLUMBIA.

DESIGN FOR A PROPELLER.

41,244.

Specification for Design.

Patented Mar. 14, 1911.

Application filed October 27, 1910. Serial No. 589,492. Term of patent 7 years.

To all whom it may concern:

Be it known that I, SPENCER HEATH, a citizen of the United States, residing at Washington, in the District of Columbia, have invented a new, original, and ornamental Design for Propellers, of which the following is a specification, reference being had to the accompanying drawing, forming a part thereof.

The figure is a plan view of a propeller, showing my new design.

The general appearance of the design is

secured in practice by combining tapered laminae of light and dark wood in such manner as to produce the tapering finger-like interior effect, as shown.

I claim:

The ornamental design for a propeller, as shown and described.

SPENCER HEATH.
